UNITED STATES PATENT OFFICE.

ALBERT C. FISCHER, OF CHICAGO, ILLINOIS.

COMBINED EXPANSION AND CONTRACTION JOINT—SEMIHEXAGONAL TYPE.

Original application filed January 3, 1922, Serial No. 526,742. Patent No. 1,655,835, dated January 10, 1928. Divided and this application filed May 9, 1927. Serial No. 190,083.

This application is a division of my application Serial No. 526,742, filed January 3, 1922 for expansion contraction joint, said application having matured into Patent No. 5 1,655,835 on January 10, 1928.

Heretofore in concrete pavements where contraction was to be provided for it has been the practice to insert a piece of metal longitudinally or transversely below the surface, so that when the concrete block or slab is poured and completed the contraction joint is not visible at the surface. After the concrete sets and contracts the function of these pieces of metal is to cause a very fine 10 crevice to develop thru the entire slab, so that it becomes visible on the surface, and functioning in this way it is styled a contraction joint.

Further developments in this style of allowing for expansion and contraction in concrete pavements can be made in which an angular or tongue and groove formation is provided, so that the projections thus developing in one concrete slab, by reason of filling 15 in these projections in the contraction joint, penetrate the other slab so that resistance is caused to any lifting action on the part of the concrete slabs. Some of these formations have been angular and some half hexagonal in shape, with straight flanges extending on either side in a vertical position when the joint is installed. These contraction joints, while causing the crevice to develop along a straight line across the concrete slab or in the surface above which the joint is inserted, do not prevent the ingress 20 of water, street acids or the like, which would tend to hastily corrode the metal contraction joint, and also enter the subsoil underneath the slab, keeping the subsoil in a constantly wet or damp condition.

My invention provides for an improved joint which has many advantages over the heretofore practiced methods, and also provides for the waterproofing of the joint automatically. These advantages are realized 45 by insertion of a bituminous slab of varying thickness, depending upon the requirements. The contraction joint flanges are imbedded 50 in the bituminous slab on either side of the projecting center. This not only tends to preserve the metal flanges but also has a tendency to protect the projecting part of the joint, because in expanding in warm weather

some of this bituminous material will ooze 55 along the surface of the uncovered metal.

It may be readily understood, of course, that a metal contraction joint may be coated with paint or bituminous material in addition to the projecting slabs of bituminous material acting both as expansion and contraction joints.

Expansion joints have usually been placed so that the upper edge of the joint was visible on the surface of the pavement, and in many 60 cases was allowed to project above the surface, so that the traffic would form a sort of mushroom top over the crevice.

It can be readily understood that the purpose of this invention is to totally submerge 70 both the contraction and expansion parts of this joint beneath the surface, so that when the concrete is finished and poured it will not be visible on the surface but will accomplish the same function, in causing a crevice 75 to form across the surface, due to contraction. It will further function by waterproofing this crevice from within, and upon expansion of the bituminous material, and also the pavement, it will cause the asphaltic 80 substance to work its way up to the crevice, so that after a hot period the bituminous material may often work its way to the surface, while the base part will have a tendency to prevent moisture from coming up, filling the 85 crevice from below, and in this manner the entire crevice will be kept waterproof, and at the same time perform both the functions of an expansion joint and a contraction joint.

In the accompanying drawing, which illustrates the preferred form of the invention herein referred to, Figure 1 is a detailed perspective view of a preformed strip of expansion joint material, which is applied to the 90 grooved portion of the contraction joint illustrated in Figure 2; and

Figure 2 is a perspective view of a portion of such a contraction joint with the strip applied thereto as stated.

Referring now to the drawing in detail. A represents a preformed strip of bituminous expansion joint which is adapted to be applied to the contraction joint B, shown in Figure 2. The joint B is made with a hexagonal tongue and groove intermediate portion C, with flat portions or flanges D and E arranged to one side thereof.

The joint B is made of metal and may be either rigid or flexible metal. I prefer to form the joint B of a single strip of sheet metal suitable for the purpose, and stamped or otherwise formed to make up the hexagonal tongue and groove portion C. The bevelled edges A¹ and A² on the strip are made to conform to the slant of the top and bottom sections C¹ and C² of the hexagonal intermediate tongue and groove C. In this way the strip A may be fitted in the groove. Ordinarily no special means are needed to secure the strip A in place, and since it is made of bituminous material it is more or less adhesive and will adhere to the metal strip, especially when it is considered that the shape of the groove will enable the strip to be more or less tightly wedged in place.

The strip A, which contains bituminous material, will not only insulate the grooved side of the joint B to an extent that any water seeping into the crevice will not trickle below the tongue and groove portion and will block this seepage, but also, under heat and pressure this bituminous material will flatten out and will flow and spread itself outwardly and along the flat flange-like portions D, thus waterproofing the crevice or crack. The flow, however, will not be sufficient to cause the bituminous material to ooze out on the top of the crevice. This flattened action of the bituminous material A is substantially a result of the wedge-shaped nature of the pocket formed in the contraction joint or plate B and are outwardly inclined sides C¹ and C² which merge into the flat plate-like flanges D and E. In addition to this function the strip A also acts as a cushion against which the projection formed in the concrete on the grooved side of the joint will abut.

I claim:

1. A contraction joint having a semi-hexagonal center with flanges extending therefrom, the center face of which is covered with an expansion joint strip and adapted to operate therewith.
2. A metallic contraction joint having oppositely extending plate-like flanges and an intermediate portion formed as a wedge-shaped depression, and bitumen containing material adherently disposed in said depression.
3. A combined contraction and expansion joint comprising, sheet material having oppositely extending flanges and an intermediate connecting portion having angular disposed sides forming a depression, and bitumen containing material adherently mounted on one of the walls of the depression.

diate connecting portion having angular disposed sides forming a depression, and bitumen containing material adherently mounted on one of the walls of the depression.

4. A combined contraction and expansion joint comprising a single piece of metal bent to form lateral extending flanges and an offset wedge-shaped pocket, and wedge-shaped slab of bituminous material adherently mounted to the basal wall of the pocket.

5. A combined contraction and expansion joint comprising a single piece of flexible sheet metal having plate-like flanges disposed in substantially a common plane and having an intermediate connecting portion of wedge-shaped formation disposed to one side on the plane of the flanges, and bitumen containing material adherently mounted in said offset portion.

6. An expansion contraction joint comprising a metal strip having a tongue on one side, a corresponding groove on the other side, and a flat portion arranged to one side of said tongue and groove, and a thickness of waterproofing material in said groove, said tongue and groove having outwardly flaring walls.

7. In a paving joint of the class described, upper and lower slab separating portions, and an intermediate wedge-shaped tongue and groove portion connecting the same, and compressible material applied to the tongue and groove portion and carried by the tongue and groove portion.

8. A device of the class described, comprising a sheet of metal bent to provide opposed flanges and an intermediate pocket on one side of the sheet, and bitumen containing material carried in said pocket.

9. A combined contraction and expansion joint comprising a preformed sheet of metal bent to provide lateral flanges and a pocket formed with an inclined wall and a preformed strip of compressible waterproofing material mounted in said pocket.

10. A combined contraction and expansion joint comprising a sheet of metal bent to form upper and lower flanges and a laterally bent portion forming a depression on one side and a projection on the other side of said sheet, and a preformed strip of waterproofing material adherently mounted in said depression.

Signed at Chicago, Illinois, this 3rd day of May, 1927.

ALBERT C. FISCHER.
